EXERCISER AND BODY BUILDER

Application filed January 21, 1930. Serial No. 422,386.

This invention relates to an athletic device for building up the muscles of the body and for reducing excess weight. The device consists of an elastic band provided with a pair 5 of knobs at the ends which can be easily gripped by the hands. When exercising various movements of the arms and body are made which will stretch the band. The work done and the strength needed to overcome the 10 resistance to the stretching of the belt will develop the muscles, build up the body, develop grace and keep the body in a trim and vigorous condition.

The device is made strong enough not to 15 tear with reasonable use and elastic enough to allow it to stretch so all parts of the body can be exercised. In practice the device is made in different degrees of elasticity to fit the physique of different versions. It is obvious 20 that a child or woman will need a more elastic band than a strong adult man.

Figure 1 is a view showing the band in use for exercising the chest muscles.

Figure 2 is a front view of the band.

25 Figure 3 is a top view thereof and

Figure 4 is a section on line 4—4 of Figure 2.

Referring now to the details, numeral 1 30 designates the band consisting of a relatively wide and thin elastic member 2 provided with a pair of T-shaped knobs 3 at the ends for being gripped in the hands. The knobs extend to the full width of the band and are curved in section so as to provide a smooth 35 surface to the hand. As seen in Figure 3 the ends 4 of the band slightly taper in cross section towards the knobs so as to reinforce this portion of the band from the extra wear which is apt to be at that point. The taper 40 starts from the line 5 and gradually thickens towards the knob.

The outside face 6 of the band is provided 45 with a top and bottom flange 7 and 8 for reinforcing the device. The inside face 9 is smooth so as not to scar or injure the skin when exercising.

It will thus be seen that I have provided a simple and efficient exercising device which can be used to develop the muscles of the body 50 and which safely can be used by children,

adults and the strong and weak. The band is made from rubber and can stretch a substantial amount without danger of tearing and breaking and in actual use has been found to be very beneficial.

55 It will be understood that the device described is capable of modification within the scope of my invention as herein set forth and claimed.

Having described my invention, I claim: 60

In an exercising device of the class described, a wide and relatively thin elastic band having T-shaped knobs at the ends, said band being thickened near the said knobs, and a flange along both edges of the 65 band on one face thereof, the opposite face being smooth.

65 In testimony whereof I affix my signature.

FRANK Poulos.
